UNITED STATES PATENT OFFICE.

PERCY W. FULLER, OF WASHINGTON, DISTRICT OF COLUMBIA, ASSIGNOR TO JOHN C. W. BEALL, OF WASHINGTON, DISTRICT OF COLUMBIA.

MAGNETO.

Application filed October 12, 1921. Serial No. 507,257.

To all whom it may concern:

Be it known that I, PERCY W. FULLER, citizen of the United States of America, residing at Washington, in the District of Columbia, have invented certain new and useful Improvements in Magnetos, of which the following is a specification.

My present invention relates to certain novel and useful improvements in magneto 10 construction.

In carrying out the present invention it is my purpose to provide a magneto construction in which the usual revolving coils or windings will be eliminated and wherein 15 by means of a mechanically operated reluctance or magnetic resistance introducing means the desired electrical current may be set up in the winding.

It is also my purpose to provide a magneto 20 construction which will embody the desired features of simplicity, efficiency and durability, which may be manufactured and marketed at comparatively small cost and wherein the component parts will be so arranged and co-related as to reduce the possibility of derangement to a minimum.

With the above recited objects and advantages in view, and others of a similar nature, the invention resides in the construction, combination and arrangement of parts hereinafter set forth in and falling within the scope of the appended claims.

In the accompanying drawing forming part of this specification:

Figure 1 is a side elevation partly in section of a magneto constructed in accordance with my invention.

Figure 2 is a sectional view on the line 2-2 of Figure 1.

Figure 3 is a fragmentary plan view showing a detail of the invention.

Figure 4 is a diagram showing the arrangement of one of the cam grooves employed in my magneto construction.

In the present instance my improved magneto embodies a pair of magnets 1-1 arranged side by side and in edge to edge contact and forming a magnetic field unit.

These magnets are of the horseshoe type and formed in the pole ends thereof centrally of the edges of the unit are axially alining openings 2-2. Mounted in these openings in some suitable manner and suitably secured therein as by bronze bushings 55 3 are pole pieces 4. These pole pieces extend

inwardly toward the center of the magnetic field unit and the inner ends thereof are in edge to edge contact, while the outer ends terminate flush with the outer surfaces of the poles of the magnetic field unit. These 60 pole pieces 4-4 are cylindrical in cross section and in the form of sleeves composed of soft iron or a similar magnetic material. In the present instance the confronting ends of the sleeve-like pole pieces 4 on the inner surfaces thereof are formed with co-operating rabbets 5 in which are mounted the secondary winding 6 and the primary winding 7, the latter being disposed within the secondary winding and having its inner 70 surface flush with the inner surfaces of the sleeve-like pole pieces, as clearly illustrated in Figure 1 of the drawing.

Mounted within the sleeve-like pole pieces 4 are cylindrical reluctance members 8 preferably composed of soft iron and having the inner ends confronting each other and the outer ends projecting through and beyond the pole pieces 4, as shown in Figure 1. These reluctance members are sleeve-like 80 in form and are supported in the pole pieces by means of bronze bushings 9, so that the reluctance members may be revolved within the pole pieces with a minimum amount of friction and also moved longitudinally 85 therein, so as to bring the confronting ends of such members toward and away from each other. The inner end of one of these members is equipped with a bronze disk 10 that acts to prevent the reluctance members 90 adhering to each other in the reciprocal movement thereof.

Extending through the alining sleeve-like reluctance members 8 is a driving shaft 11 formed of bronze or other non-magnetic material and the ends of this shaft are suitably mounted in anti-friction members 12 carried by a base 13 upon which the ends of the horseshoe magnets forming the field unit rest, this base being of any suitable or 100 conventional construction.

In the present instance the reluctance members 8 are secured to the shaft 11 by means of splines 14 which act to revolve the reluctance members with the shaft and at 105 the same time permit rectilinear movement of the reluctance members relative to the shaft.

Surrounding the reluctance members adjacent to the outer ends thereof are collars 110

15 circular in cross section and having the inner ends thereof threaded into the outer extremities of the pole pieces 4, as at 16, or otherwise connected thereto.

5 In this embodiment of my invention the inner ends, that is to say, the ends of the collars 15 in proximity to the legs of the field unit, are formed with outwardly extending flanges 17, while the outer ends 10 of the collars 15 rest within anti-friction bearing members 18 of appropriate construction that are carried by disks 19 formed integral with or otherwise connected to the outer extremities of the reluctance members 15. Interposed between the collars 15 and the reluctance members 8 are bronze bushings 20 that constitute bearings for the outer extremities of the reluctance members and co-act with the bushings 9 in order to permit 20 free rotation and rectilinear movement of the reluctance members.

In the construction that I have selected for illustrative purposes, the collars 15 constitute not only bearing members for the 25 outer ends of the reluctance members, but also act as a means to impart a reciprocal movement of the reluctance members 8, and for this purpose the inner walls of the respective collars 15 are formed with cam-like grooves 21 in which ride rollers 22 journaled upon pins carried by the reluctance members and projecting outwardly from such members, as clearly shown in Figure 1 and Figure 4. Springs 23 surround the respective collars 15 and the inner end of each spring bears against the flange 17 while the outer end engages the corresponding anti-friction bearing member 18, so as to exert an outward pressure upon such 40 bearing member, and thereby hold the reluctance member 8 at its limit of outward movement, so that the inner ends of such members will be normally spaced apart as shown in Figure 1.

45 In this instance the cam grooves 21 in the respective collars 15 are spaced apart at an angle of 90° so that the magneto may be used with a vertical cylindrical motor. When, however, my improved magneto is to be used 50 with a motor of the V-type, then the angle at which the cam grooves are arranged is changed. In order to change such angle the pole pieces 4 to which the collars 15 are rigidly attached are adjusted circumferentially relative to each other and locked at such adjusted position. It is conceivable 55 that any means may be employed for locking these pole pieces, but in this form of my invention I show a latch member 24 that is fixedly secured to the inner end of one of the pole pieces and that is interchangeable with notches 25 formed in the corresponding end of the other pole piece, as depicted in Figure 3 of the drawing.

65 In the operation of my improved mag-

neto the shaft 11 is driven in some suitable manner, as by a gear 26 formed on the periphery of one of the disks 19 and designed to mesh with a similar gear driven from the crank shaft of the internal combustion 70 motor. In the operation of the shaft 11 the reluctance members 8, owing to the spline 14, revolve with the shaft, and in the revolution of the reluctance members 8 the rollers 22 riding within the cam groove 21 oscillate 75 the reluctance members. Due to the position of the cam grooves 21 with respect to each other one reluctance member remains stationary, and vice versa. In the continued operation of the reluctance members it will be seen that reluctance is removed from the magnetic circuit as the inner ends of the members move together, thereby making two magnetic paths, one inside and the other 80 outside of the coils 6 and 7. On the other hand, when the inner ends of the reluctance members separate, destroying the shunt magnetic path inside of the coils, then a reluctance or magnetic resistance is introduced into the inside magnetic circuit thereby 85 generating an E. M. F. of high tension within the coils due to the flux linkage of the magnetic lines sweeping by the coils to the outside magnetic path.

In order to change the time of the reluctance one of the collars 15 is provided with an arm 27 that may be connected with a suitable hand controlled lever, so that the collars 15 and the field pieces 4 may be rotated within the openings formed in the field unit, in order to change the position 100 of the cam grooves 21 with respect to the rollers, so that the spark may be obtained in the cylinders of the motor at the desired period in the travel of the piston, as is 105 readily understood to those skilled in the art to which the invention relates.

It will be seen that I have provided a magneto construction wherein the usual coils constituting the armature remains stationary 110 in the magnetic field set up by the field unit, while the necessary current is generated in such coils through the medium of a reluctance introducing means which not only revolves within the coils but also reciprocates therein, so as to set up and diminish the necessary magnetic resistance to 115 influence the flow of current through the coils forming part of the outside circuit.

While I have herein shown and described 120 one particular form of my invention by way of illustration, I wish it to be understood, that I do not limit myself to the precise details of construction herein described and delineated in the accompanying drawings, 125 as modifications and variations may be made within the scope of the claims without departing from the spirit of the invention.

I claim:

1. In magneto construction, a magnet de- 130

- signed to produce a magnetic flux and formed with alining openings adjacent to the ends thereof, pole pieces mounted in said openings and capable of movement therein, 5 windings within said pole pieces and arranged within the influence of the magnetic flux set up by the pole pieces of said magnet, mechanically operated means within said windings for varying the flow of the 10 magnetic flux through the same whereby an electrical current will be produced within said windings, and means for moving said pole pieces relative to said first mentioned means to change the timing of the current 15 in the outside circuit.
2. In a magneto construction, a magnet designed to produce a magnetic flux and formed with alining openings adjacent to the ends thereof, pole pieces mounted in said 20 openings, windings within said pole pieces and arranged within the influence of the magnetic flux set up by the pole pieces of said magnet and mechanically operated means within said windings for varying the 25 flow of the magnetic flux through the same whereby an electrical current will be produced in said windings, said mechanically operated means comprising a shaft extending through said pole pieces axially thereof, 30 sleeve-like reluctance members encircling said shaft within said pole pieces, respectively, and splined to said shaft, and means for oscillating said reluctance members on said shaft in the rotation of the latter and 35 means for rotating said shaft.
3. In a magneto construction, a magnet designed to produce a magnetic flux and formed with alining openings adjacent to the ends thereof, pole pieces mounted in 40 said openings, windings within said pole pieces and arranged within the influence of the magnetic flux set up by the pole pieces of said magnet and mechanically operated means within said windings for varying the 45 flow of the magnetic flux through the same whereby an electrical current will be produced in said windings, said mechanically operated means comprising a shaft extending through said pole pieces axially thereof, sleeve-like reluctance members encircling said shaft within said pole pieces, respectively, and splined to said shaft, said last named means comprising collars surrounding said reluctance members, respectively, at the outer ends thereof and connected to said pole pieces and formed with cam-like grooves, and rollers carried by said reluctance members riding in said grooves, and means for driving said shaft.
4. In a magneto construction, a magnet 60 designed to produce a magnetic flux and formed with alining openings adjacent to the ends thereof, pole pieces mounted in said openings, windings within said pole pieces and arranged within the influence of 65 the magnetic flux set up by the pole pieces of said magnet and mechanically operated means within said windings for varying the flow of the magnetic flux through the same whereby an electrical current will be produced in said windings, said mechanically operated means comprising a shaft extending through said pole pieces axially thereof, 70 sleeve-like reluctance members encircling said shaft within said pole pieces, respectively, and splined to said shaft, said last named means comprising collars surrounding said reluctance members, respectively, at the outer ends thereof, and connected to said pole pieces and formed with cam-like 75 grooves, rollers carried by said reluctance members riding in said grooves and means for driving said shaft, and means whereby said sleeves and pole pieces may be shifted circumferentially relative to said sleeve-like reluctance members to change the timing of the current in the outside circuit.
- In testimony whereof I have hereunto set my hand in presence of two subscribing witnesses.

PERCY W. FULLER.
